 Telephone and Telegraph Company, a corpora-
 tion of New York

Application June 7, 1941, Serial No. 397,038

5 Claims. (Cl. 179—58)

This invention relates to telephone circuits and systems, and more particularly to arrangements for improving such circuits and systems so that signaling between the subscriber and the telephone operator may be accomplished more efficiently, especially in cases where the subscriber's loop is a long one, or is formed of small gauge wire.

As is well known, the circuit of the A operator's position includes a battery, usually of 24 volts, a repeating coil, and a supervisory relay, the latter relay being energized by current from the battery when the subscriber's station circuit is connected to the A operator's cord circuit. This supervisory relay is of the usual single inductive winding type (with a bridged non-inductive winding) and it includes a core of iron which has some residual magnetism after the relay winding has become deenergized. For toll switching operations the subscriber's station circuit is also connected to the B operator's trunk circuit which usually includes a battery of higher voltage of, for example, 48 volts. This battery voltage is also applied to the winding of the supervisory relay in the A operator's cord circuit during the interval when both the cord and trunk circuits are simultaneously connected to the subscriber's station circuit. The two voltages are poled with respect to the supervisory relay winding so as to oppose each other, and hence the larger voltage from the B operator's trunk circuit will dominate and therefore reverse the previous magnetization of the relay core. In other words, the application of the higher voltage to the supervisory relay winding during toll switching operations produces a net effect in the magnetic structure of the supervisory relay which is opposite to that caused alone by the lower voltage of the A operator's circuit. And after the cord and trunk circuits become disconnected from each other, the relay core will have residual magnetism poled opposite to its former polarity.

It has been discovered that because the core of the supervisory relay of the A operator's cord circuit obtains a reverse "soak" when the B operator's trunk circuit, (also known as a toll switching trunk) is plugged into the multiple jack of the subscriber's circuit, more current is required to operate the supervisory relay soon thereafter than under ordinary conditions. Because of this difficulty, should the A operator's cord circuit involved in the toll call be soon afterwards used to answer a subsequent call from a subscriber, the supervisory relay may not operate satisfactorily. In that event the operator may disconnect her

5 circuit from the subscriber's line while the subscriber remains on the line. This adverse condition has become especially troublesome on the longer subscribers' loops as well as on loops of smaller gauge wire which are rapidly coming into more extensive use in telephone systems.

It is an object of this invention to eliminate the adverse conditions just referred to by shunting the higher voltage supplied by the B operator's trunk circuit from the winding of the supervisory relay of the A operator's cord circuit.

It is another object of this invention to arrange the circuit of the supervisory relay so that only the voltage in the A operator's cord circuit may be applied to its winding. This may be accomplished, for example, by adding elements to the circuit which will freely transmit the current of the cord circuit battery to the winding of the relay, and will also by-pass current from the higher voltage battery of the B operator's trunk circuit around the relay winding.

This invention will be better understood from the detailed description hereinafter following when read in connection with the accompanying 25 drawing showing one embodiment of the invention merely for the purpose of illustration.

Referring to the drawing, the local subscriber's circuit designated S is shown at the right, this circuit including the usual induction coils Y₁, a 30 telephone receiver R, a telephone transmitter T, a ringer D, switch hook H and the condenser C₁. The telephone set S may be connected in the usual way over the subscriber's loop to the tip and ring sides of the jack J₁ at the central office as shown. The A operator's cord circuit includes, among other things, the usual repeating coils Y₂ and Y₃, the battery B₁, ordinarily of around 24 volts, the supervisory relay W₁, the inductive winding of which is shunted by a non-inductive 35 resistor X₁, and the plug P₁ as shown. The B operator's trunk circuit for toll switching operations includes the usual repeating coils Y₄ and Y₅, the condensers C₂ and C₃, the relay W₂ and the grounded battery B₂, which is ordinarily of 40 about 48 volts, a voltage which is higher than that of the battery B₁ of the A operator's cord circuit. The B operator's trunk circuit terminates in a plug P₂, which may engage the multiple jack J₂ associated with the local subscriber's circuit S.

The A operator's cord circuit also includes two rectifiers or other non-linear devices designated Z₁ and Z₂. The rectifier Z₂ is so poled that it will freely transmit current from battery B₁ 45 through the winding of the supervisory relay 50 Z₁.

W₁, while at the same time opposing any flow of current from the battery B₂ of the B operator's trunk circuit through the relay winding, as will be more clearly shown hereinafter. The devices Z₁ and Z₂ may be rectifiers or varistors of any type well known in the art. They are preferably assembled so that the positive terminal of one of the rectifiers is directly tied to the negative terminal of the other rectifier and hence comprise a three-terminal combination.

When the local subscriber at station S signals the A operator as, for example, by removing the receiver R from the switch hook H, the relay W₃ will immediately operate, current flowing from the battery B₃ through the right-hand winding of relay W₃, the lower armature and back contact of the cut-off relay W₄, the lower conductor of the subscriber's loop, the transmitter T, the switchhook H, the left-hand winding of the induction coil Y₁, the upper conductor of the subscriber's loop, the upper armature and back contact of the relay W₄, the left-hand winding of relay W₃ and ground. The operation of the relay W₃ will illuminate the lamp L₁ because of the flow of current from the battery B₄ to that lamp when the armature of relay W₃ closes its contact. The lamp L₁ will attract the A operator's attention and she will then insert her plug P₁ into the subscriber's jack J₁. After this connection is established the lamp L₂ will remain extinguished although current flows from battery B₅ through lamp L₂, resistor X₂, the sleeve contacts of plug P₁ and jack J₁, the winding of the cut-off relay W₄ and ground. The lamp L₂ remains extinguished because of the presence of resistance X₃ in the lamp L₂ circuit. The relay W₄ will, however, operate and release the relay W₃. The release of the relay W₃ will extinguish the lamp L₁. The relay W₁ will also operate, current for which is supplied by battery B₁ over a circuit which includes the right-hand winding of the repeating coil Y₃, the rectifier Z₂, the winding of relay W₁, the ring contacts of plug P₁ and jack J₁, the lower conductor of the subscriber's loop, the transmitter T, the switchhook H, the left-hand winding of induction coil Y₁, the upper conductor of the subscriber's loop, the tip conductors of jack J₁ and plug P₁, the right-hand winding of repeating coil Y₂ and ground. The relay W₁ will remain operated as long as the plug P₁ and jack J₁ are in engagement and the subscriber keeps his receiver R off the switchhook H. The battery B₁ will now be supplying current through the winding of relay W₁ to the transmitter T at the subscriber's set S to facilitate the transmission of speech currents.

Assume now that the local subscriber at station S informs the operator of his desire to make a toll call. The A operator will then establish the connection to the toll operator who will then instruct the B operator to insert plug P₂ into the subscriber's multiple jack J₂. When this happens, both the A operator's cord circuit connected to plug P₁ and the B operator's trunk circuit connected to plug P₂ are simultaneously connected to the subscriber's set S. Current then flows from battery B₃ not through the winding of relay W₁, as in prior art schemes, but through the rectifier Z₁ instead. The circuit carrying the current of battery B₂ includes the winding of relay W₂, the right-hand winding of the repeating coil Y₅, the ring contacts of plug P₂ and jack J₂, the ring contacts of jack J₁ and plug P₁, the rectifier Z₁, the right-hand winding of repeating coil Y₃, battery B₁ and ground.

It will be observed that when the circuits of the A cord and the B trunk are both connected to the subscriber's set S, the current from battery B₂ will traverse the rectifier Z₁ and, because of the polarity of the rectifier Z₂, will be unable to traverse the winding of the relay W₁. Were the rectifiers Z₁ and Z₂ omitted, the greater voltage of battery B₂ would overcome the smaller voltage of battery B₁ when applied simultaneously to the winding of the supervisory relay W₁. Hence the core of the relay W₁ would be so magnetized as to be unable to operate satisfactorily when the A cord is subsequently connected to another subscriber over a long loop.

15 The application of two opposing voltages, such as those of batteries B₁ and B₂, to the winding of relay W₁ has been especially troublesome heretofore where the subscriber's loops approach the maximum resistance of around 750 ohms, or when 20 the newer types of loops of smaller gauge wire were installed. The supervisory relay of the telephone plant is not adaptable for adjustment to operate satisfactorily with loops of higher resistance under the conditions hereinabove referred to. By restricting the voltage applied to the relay winding W₁ to that of the local battery B₁, it is unnecessary to undergo the expense of replacing existing supervisory relays. The 25 circuit of this invention will allow the supervisory relay to respond accurately to every movement of the switchhook H with loops of higher resistance.

It will be apparent that when the A operator removes her plug P₁ from jack J₁ the supervisory 30 relay W₁ will then release. When this happens the lamp L₂ will remain extinguished. The relay W₁ will operate only in response to current from battery B₁.

It has been pointed out that lamp L₂ remains 40 extinguished when plug P₁ engages jack J₁ to connect the subscriber's set S to the A operator's cord circuit. In prior arrangements which did not include devices Z₁ and Z₂, the addition of the B operator's trunk circuit caused current from 45 battery B₂ to flow through the winding of relay W₁ and retain relay W₁ in operated condition. Consequently lamp L₂ remained extinguished and the A operator was later signaled to disconnect her plug P₁ from jack J₁ over the other end of the 50 A operator's cord circuit (not shown).

In the circuit including the devices Z₁ and Z₂, however, the addition of the B trunk circuit to that of the A cord circuit and the subscriber's set S causes the relay W₁ to release because current is no longer able to traverse its winding due to the presence of device Z₂. Hence, the lamp L₂ will become illuminated instantly and promptly notify the A operator to remove her plug P₁ from jack J₁. The lamp L₂ will of course 55 become extinguished only after the A cord circuit is removed from jack J₁.

It will thus be apparent that the inclusion of devices such as Z₁ and Z₂ automatically gives the A operator a prompt signal to disconnect her circuit from the subscriber's line. No supervision 60 from other operators is required to effectuate this signaling operation. This is an important feature of this invention.

Although two rectifiers or non-linear devices 65 such as Z₁ and Z₂ have been described as a composite structure to be used in practising this invention, it will be understood that the shunt device Z₁ may be employed without the series device Z₂, and that the series device Z₂ may be 70 employed without the shunt device Z₁. If but one

device is used, there will be a substantial improvement observed over prior art schemes operating without such devices, but the non-linear device will have to be of relatively large physical dimensions, so as to obtain satisfactory characteristics. Such large devices are unfeasible and impractical for insertion in available switchboard space. But if two devices such as Z_1 and Z_2 are used together, as shown and described, the two devices so used will each be relatively small and inexpensive and they will operate much more effectively than will one such device alone.

It will be understood that the repeating coils Y_2 and Y_3 may be one and the same repeating coil and that repeating coils Y_4 and Y_5 may also be one and the same repeating coil.

While this invention has been shown and described in certain particular arrangements merely for the purpose of illustration, it will be understood that the general principles of this invention may be applied to other and widely varied organizations without departing from the spirit of the invention and the scope of the appended claims.

What is claimed is:

1. In a telephone system, an A operator's cord circuit including a battery and a relay, a B operator's trunk circuit including a battery of higher voltage, a circuit interconnecting the A operator's circuit to the B operator's circuit, and rectifying apparatus connected to the winding of said relay and poled so as to permit the transmission of current from the battery of the A operator's circuit through the relay winding while substantially suppressing the flow of current from the battery of the B operator's circuit through the relay winding.

2. In a telephone system, the combination of a subscriber's circuit, a first trunk circuit, a second trunk circuit, first and second batteries connected in said first and second trunk circuits, respectively, a circuit interconnecting the first trunk circuit with the subscriber's circuit, the latter circuit including a rectifier so poled as to permit signaling between the interconnected circuits, a relay the winding of which shunts said rectifier, a second rectifier connected in series with the winding of said relay, a circuit connecting the second trunk circuit to the interconnected circuit, the second rectifier being so poled as to

oppose the flow of current from the second battery through the relay winding of current.

3. In a telephone system, the combination of a first trunk circuit, a second trunk circuit, a subscriber's set, first and second batteries of different voltages, a relay which is connected along with said first battery in the first trunk circuit, the second battery being connected to the second trunk circuit, and means to permit current from the first battery to flow substantially freely through said relay winding while opposing the flow of current from the battery of the second trunk circuit through said relay winding when the two trunk circuits are connected to each other through the circuit of the subscriber's set.

4. In a signaling system, the combination of a first circuit which is supplied with voltage of a predetermined magnitude, a second circuit which is supplied with voltage of a higher predetermined magnitude, a relay connected to the first circuit, and means to prevent the magnetization of the core of said relay by the voltage of higher predetermined magnitude when said first and second circuits are connected to each other, said means including a non-linear device which is connected in series with the winding of said relay so that the voltage supplied to said first circuit will traverse the winding of said relay, said non-linear device being poled so that the voltage of the second circuit cannot be applied to the winding of said relay.

5. In an electrical system, the combination of a relay having a core which has a substantial residual magnetic effect after it has been energized, two sources of voltage which are connected to the relay winding so as to produce mutually opposing voltage effects on said relay winding, and means to eliminate the voltage effect of one of said sources so as to avoid any residual magnetic effect in said core in response to said latter voltage effect, said means including a rectifier arrangement serially interconnecting the latter source of voltage and the relay winding and so poled as to prevent the latter voltage effect from magnetizing the relay core, said rectifier arrangement permitting the other voltage effect to energize the relay core.
